UNITED STATES PATENT OFFICE.

SVEN JULIUS STRID, OF CHICAGO, ILLINOIS, ASSIGNOR TO FRED MATHEWS, OF CHICAGO, ILLINOIS.

ADAPTER FOR BRAKE-GEAR MOUNTINGS.

Application filed December 11, 1925. Serial No. 74,748.

To all whom it may concern:

Be it known that I, SVEN JULIUS STRID, a citizen of the United States of America, residing at Chicago, in the county of Cook and State of Illinois, have invented a new and useful Improvement in an Adapter for Brake-Gear Mountings, of which the following is a full, clear, and exact description, such as will enable others skilled in the art to make and use the same.

My present invention relates to means for readily mounting the gearing of a railway car brake, and has special reference to what I term an "adapter", the use of which permits the manufacturer to produce the gears, housing, etc., as a unit, so that one structure may be used for a number of types of car construction, and with my "adapter" this unit may be readily secured to the particular car to be equipped.

The use of this structure effects a considerable saving in the manufacture of these gear structures, because of the fact that it has heretofore been the general practice to practically re-design the housing of the gear mechanism for each type of installation required, which of course adds considerably to the cost of production. With the present structure, with the gears, housing, etc., furnished as a unit, it is only necessary to substitute the particular adapter for the particular installation. Also the use of the hereinafter described structure makes it possible to quickly detach and remove the unit containing the gears, housing, etc., from the car without the necessity of having to cut rivets, or remove bolts and nuts for the reason that the adapter, while it is positively interlocked with the housing, may be readily disassembled by the simple removal of a pin.

I prefer to carry out my invention and to accomplish the divers objects thereof in substantially the manner hereinafter fully described and as more particularly pointed out in the claims, reference being here made to the accompanying drawings that form a part of this specification.

In the drawings:

Figure 1 is a top plan of a brake gear housing and my adapter, the entire structure being removed from the car.

Figure 2 is a vertical longitudinal side

view of the structure illustrated in Figure 1, with the end portions thereof in longitudinal vertical section and showing a portion of the car in broken lines.

Figure 3 is a front end elevation of the top section of the housing and my adapter.

Figure 4 is a vertical side elevation drawn to a smaller scale and showing a complete gear unit and my adapter installed at the end of a car the latter being shown as a fragmentary corner thereof.

The drawings are in a sense merely schematic for the purpose of illustrating a typical or preferred embodiment of my invention, and in these drawings I have employed similar reference characters to designate the same parts wherever they appear throughout the several views.

My invention, as will be understood, is capable of use, with but slight change, to divers types of car construction, and for convenience I have herein shown a car in which the transverse end-sill is of the channel type, which may be an angle, I-beam, of the like, with the web 5 vertically disposed and with the lower flange 6 projecting horizontally in an outward direction from the car. The brake operating mast 7 is positioned outside the vertical plane of the end of the car and beyond the flange 6 of the sill, and secured to the inner face of the web 5 of the sill is a triangular gusset or bracket consisting of a vertical plate 8 extending transverse to the sill with its vertical flange 9 secured to the sill web and with its lower horizontal flange 10 extending longitudinally of the car with its under surface in the same plane with and forming a continuation of the lower surface 00 of the flange 6 of the sill.

The gearing in this particular instance is illustrated in a conventional manner and is preferably of the type fully illustrated and described in United States Letters Patent No. 1,508,564, which was issued to Fred Mathews on September 18th, 1924, for a "gearing", and consists briefly of driving and driven gear members each having concentric and eccentric edge portions, the latter portions being preferable obliquely disposed with respect to the axis of rotation of the respective member. The brake mast 7

is operatively connected to the driving gear

member and the driven gear member is mounted upon a spindle 11 the ends of which are supported in the housing.

The gear housing has bottom castings consisting of a horizontal plate 12, in which the lower end of the mast is preferably supported, and an arm 13 extends inwardly and is deflected downwardly from the plate to provide a support and journal for the spindle 11 and the driven gear member thereon, while the edges of said plate are provided with upstanding walls 14 that overlap and are secured to the vertical depending walls 15 of the horizontal plate 16 of the top casting of the housing. The plate 16 has a neck 17 projecting inwardly longitudinally of the car and in alignment below the flange 10 of the gusset or bracket on the sill, and there is a transverse embossment 18 near the end of the neck to receive the upper end of the driven gear spindle 11. Beyond the embossment and transverse to the bore thereof is a hollow knuckle or eye 19, the purpose of which will hereinafter appear, and at the opposite or outer edge of the top casting are one or more pockets 20, (two of said pockets being illustrated) that open upon the sides of enlargements or blocks formed integral with and arise from the upper face of the plate (Fig. 2). The structure heretofore described, consisting of the two-piece housing, and the driving and driven gear members are preferably standardized and assembled as a unit and kept in stock for divers types and constructions of cars with which the unit is to be equipped, but because of the fact that the underframe and bodies of the cars vary in design it is necessary to provide different means for attaching and mounting the gear unit to each type of car and underframe or modified constructions thereof. To this end I have designed what may be termed an "adapter" which will now be described and which may be of divers shapes and dimensions so as to provide a ready means for installing the standardized gear unit upon different makes of cars or underframes.

This "adapter" preferably comprises a plate 21 of substantially rectangular shape that fits the upper surface of plate 16 of the top casting and its edge adjacent to the pockets 20 is provided with lugs or shoes 22 that fit into said pockets and interlock therewith. A reduced neck 23 extends from the opposite edge of the adapter plate 21 and near its extremity which extends beyond the knuckle 19 is provided with an aperture 24 to receive or rivet 25 that also passes through the horizontal flange 10, of the gusset whereby the adapter is securely attached to the underframe. The sides of the neck 23 are provided with depending flanges 26 that extend outside the adjacent portions of the neck 17 of the top casting, which flanges are

apertured in alignment with the bore of the knuckle 19 so that a removable pin 27 may be inserted through the knuckle and said apertures to connect the top casting to the adapter. For the purpose of reinforcing the structure against the longitudinal pull incident to the operation of the brake I have provided a bracing shoe in the form of a vertical plate or abutment 28 that engages the web 5 of the sill and is provided with reinforcing ribs 29 that slopes downwardly from the abutment towards the outer edge of the adapter 21. As will be observed in Figures 2 and 4 of the drawings the lower edges of the ribs 29 conform substantially to the adjacent surface of the lower flange 6 of the sill so that a ready fit is obtained.

In assembling the structure the adapter is usually mounted upon the sill or other adjacent portion of the car by inserting the plate 21 and the neck 23 under the sill and gusset until the abutment wall engages the web 5 of the sill to which it is secured by bolts 30 and the bolts 25 are passed through the neck and secure the inner end of the adapter to the gusset. The gear unit may now be removably mounted by interlocking lugs 22 with the pockets 20 and then inserting the transverse pin 27 through the knuckle 19 and the apertures in the depending walls 26 of the adapter neck. Should it be desired to remove the gear unit in case of accident or replacement it is only necessary to knock out the pin 27, which permits the interlocking parts at the opposite end of the structure to be disengaged.

It will be understood from the foregoing that the adapter will have to be necessarily modified according to the type or construction at the end of the car being equipped, the essential feature of the adapter being that it is provided with means for readily and removably interlocking the same with the gear unit as well as with dependable means for connecting it to the car and bracing the structure against the pull instant to applying the brakes.

What I claim is:—

1. The combination with a railway car underframe, of a gear unit for actuating the brake, an adapter structure secured to the underframe, and means on the unit and adapter to interlock the one with the other and permit the unit to be readily removed from the car.

2. The combination with a railway car underframe, of a gear unit for actuating the brake, an adapter structure secured to the underframe, an abutment on said adapter to engage a transverse member of the underframe, and means on the unit and the adapter to interlock the one with the other and permit the unit to be readily removed from the car.

3. The combination with a railway car un-

derframe, of a gear unit for actuating the brake, a plate secured to the underframe, a braced abutment carried by said plate and engaged with a portion of the underframe, 5 and lugs and pockets providing interlocking connection between said unit and plate.

4. The combination with a railway car underframe including an end-sill, of a gear for actuating the brake and having an extension 10 projecting under the end-sill a plate secured to the end-sill and having an extension projecting back of the same, a member secured to and projecting from the end-sill to which said extension is secured, an abutment carried by the plate and engaged with the end-sill, interlocking pockets and lugs on said unit and plate, and a removable pin connecting the extensions of said unit and plate, whereby the unit may be readily disconnected from the other structure. 15

5. The combination with a railway car underframe including an end-sill, of an adapter for removably mounting a brake gear unit thereon, said adapter consisting of a plate secured to and extending under the end-sill, an abutment carried by said plate and en-

gaged with the end-sill, and means on said plate to interlock with counterpart portions of the gear unit.

6. The combination with a railway car underframe including an end-sill of an adapter for removably mounting a brake gear unit thereon, said adapter consisting of a plate secured to the end-sill, an extension projecting from an edge of said plate under the end-sill longitudinally of the car, an abutment carried by said plate and engaged with the outer face of the end-sill, and means on opposite edge of said plate to interlock with counterpart portions of the gear unit. 30

7. An adapter for removably mounting a brake gear unit upon a railway car comprising a polygonal plate, an extension projecting from one edge thereof, lock lugs projecting from the opposite edge of said plate, 35 and an abutment carried by said plate intermediate said extension and lugs. 40

Signed at Chicago, in the county of Cook, and State of Illinois, this 27th, day of November 1925.

SVEN JULIUS STRID.
